Application filed December 26, 1901. Serial No. 87,382. Term of patent 3½ years.

To all whom it may concern:

Be it known that I, ADOLPH PETZOLD, a citizen of the United States, residing at Philadelphia, Pennsylvania, have invented and produced a certain new and original Design for a Rug, of which the following is a full, clear, and exact description, reference being had to the accompanying drawing, forming a part of this specification.

10 My invention relates to the surface ornamentation of a woven rug; and it consists of the design therefor shown in said drawing. In its essentials it consists of the following distinguishing features—namely, a narrow border line *a*, inwardly irregular, as at *a'*,

within the same an inner series of connected scrolls *b*, and within the center space formed by the latter as a whole is a large floral figure *c*, composed of leaves and flowers.

I claim—

20 The design for a rug substantially as shown and described.

In testimony whereof I have hereunto affixed my signature this 4th day of December, A. D. 1901.

ADOLPH PETZOLD.
